UNITED STATES PATENT OFFICE.

MERTON L. EMERSON, OF BRAINTREE, MASSACHUSETTS, ASSIGNOR TO AMERICAN PNEUMATIC SERVICE COMPANY, OF BOSTON, MASSACHUSETTS, A CORPORATION OF DELAWARE.

PNEUMATIC-DESPATCH-TUBE APPARATUS.

1,107,661.

Specification of Letters Patent. Patented Aug. 18, 1914.

Application filed December 6, 1911. Serial No. 664,147.

To all whom it may concern:

Be it known that I, MERTON L. EMERSON, of Braintree, in the county of Norfolk and State of Massachusetts, have invented certain new and useful Improvements in Pneumatic-Despatch-Tube Apparatus, of which the following is a specification.

My invention relates to improvements in pneumatic despatch tube apparatus and especially to blower unloading devices for use 10 in connection therewith.

The object of this invention is to load and unload the blower intermittently; that is, to allow the blower to run free, and when it is 15 desired to load the same, to automatically throw it into communication with the load; in pneumatic tube systems employing my invention, when it is desired to despatch carriers, the blower is thrown into communication with the transit tube and after a pre-determined interval after the insertion of the last carrier, the blower is automatically thrown out of communication with the system and allowed to run free.

25 In the accompanying drawings which illustrate a construction embodying my invention, Figure 1 is a diagrammatic view illustrating my device connected to a pneumatic tube system through which carriers are transmitted by compressed air, with the parts in the position when the blower is running free and no carriers are being transmitted. Fig. 2 is a detail view in section showing the position of the timing device when the blower is running loaded, that is, when carriers are being transmitted 30 through the system.

Like letters of reference refer to like parts throughout the several views.

40 In the form of apparatus shown in the drawings, A represents the sender located at each end of the line, which consists of a loop line of tubing A² extending between two stations.

45 A' is an electric switch at each sender which may be operated by the insertion of a carrier into the sender for transmission, or by hand if desired.

The electric motor B is adapted to operate 50 the compressor C which is provided with a check valve C' at the intake which allows

air to flow in but prevents its escape. The pipe C³ leads from compressor C to the line of tubing A² and near the compressor is connected the pipe C⁴ which leads from pipe C³ to the air storage tank D; this pipe has a check valve C² which allows pressure to accumulate in the tank D but prevents its return to the compressor.

On the switch board E is mounted the timing mechanism F.

G⁴ represents the main feed wires running to the motor B.

H H' are auxiliary electric circuits which control the timing mechanism.

A carrier to be despatched is placed in the sender A and momentarily closes the switch A' as it passes over it thereby closing the auxiliary circuits H H' and causing the plunger F³ in the solenoid F' to be drawn 65 upwardly; this movement opens the valve F⁵ (see Fig. 2) and permits the air supply in the storage tank D to pass through pipe F² to the bottom of the cylinder F¹². The compressed air then forces the floating piston F⁴ to the top of the cylinder F¹² as the space above the piston F⁴ is open to the atmosphere through the vent F⁸. Below the piston F⁴ is a valve casing F⁶ containing the piston valve F¹¹ and spring F⁷; this piston 70 valve F¹¹ controls the flow of compressed air from the pipe F² to the pipe J or to the pipe K. The stem F¹³ extends into the bottom of the cylinder F¹² in such a way that when the floating piston F⁴ is at its lowest 75 position, the piston valve F¹¹ is pushed down against the spring F⁷ thereby closing communication between the pipe F² and the pipe K (see Fig. 1) so that air cannot pass from pipe F² into pipe K, but passes from pipe 80 F² to pipe J into the valve casing K' forcing up piston k and bringing the pistons k' k² (carried by piston rod K²) into the position shown in Fig. 1; at the same time, compressed air from the tank D passes by 85 the pipe K³ into the pipe K⁴ and through the bottom of the valve casing K⁵ and port L² into the bottom of cylinder L lifting the piston L³ to its upper position as shown in Fig. 1 with the gate L⁶ in its upper position 90 so that the blower C communicates directly with the atmosphere through the passage L⁷

100

thus short-circuiting the flow of air and unloading the blower.

As the circuit is momentarily closed, as explained above, and the piston F⁴ is raised to the position shown in Fig. 2, piston valve F¹¹ moves to the position shown in Fig. 2 under the influence of spring F⁷ so that the pipe J is cut off from the pipe F² and compressed air passes by the pipe K to the top of the valve casing K' and acting upon the piston k drives the same downwardly with the pistons k' k² as shown in Fig. 2 and compressed air passes through the pipe K³ from the tank D into the valve casing K⁵ through port L' to the top of cylinder L driving piston L³ downwardly and closing the gate L⁶ as shown in Fig. 2 and thereby cutting off the blower from communication with the atmosphere.

The drop of the piston F⁴ is regulated in speed by the controlling valve P communicating with the atmosphere, so that for long lines, the valve P is set so that the air escapes to the atmosphere slowly, while for short lines, the valve is set so that the air escapes more rapidly. The opening of the gate L⁶ so as to throw the blower into communication with the atmosphere, is thus regulated for different lengths of lines, that is, the gate L⁶ opens and the blower is thrown into communication with the atmosphere and allowed to run free after the lapse of a predetermined interval after the insertion of the last carrier.

M is an exhaust pipe to the atmosphere.

When the blower is unloaded or running free, the amount of current used is at a minimum, but when carriers are inserted into the tube lines and the air switched through the tube line or lines for driving the carriers, the resistance or load is increased with a proportionate increase of power in the current until the air current is automatically switched and the load is removed from the blower reducing the power again to the minimum.

The operation of despatching carriers is identical at both ends.

I do not limit myself to the arrangement and construction shown as the same may be varied without departing from the spirit of my invention.

Having thus described the nature of my invention and set forth a construction embodying the same, what I claim as new and desire to secure by Letters Patent of the United States is:

1. In a pneumatic despatch tube apparatus, a substantially constantly-operating blower or pump for compressing air and normally communicating with the atmosphere, a conduit, means for switching said blower or pump into operative communication with said conduit, and co-acting means, independent of the travel of the carrier, for

automatically switching said blower or pump from operative communication with said conduit to the atmosphere.

2. In a pneumatic despatch tube apparatus, a substantially constantly-operating blower or pump for compressing air and normally communicating with the atmosphere, a conduit, means for switching said blower or pump into operative communication with said conduit, means for automatically switching said blower or pump from operative communication with said conduit to the atmosphere, and means for timing the period of communication of said blower or pump with said conduit. 80

3. In a pneumatic despatch tube apparatus, a tube for the transmission of carriers, a substantially constantly-operating blower or pump for compressing air, means normally connecting the said blower or pump with the atmosphere, means for switching a portion at least of said atmospheric connection into operative communication with said transmission tube to establish a current of compressed air through said tube for transmitting carriers, and means co-acting with said last mentioned means and independent of the travel of the carrier for automatically switching back said current of air to the atmosphere. 90

4. In a pneumatic despatch tube apparatus, a tube for the transmission of carriers, a substantially constantly-operating blower or pump for compressed air, means normally connecting said blower or pump with the atmosphere, means for switching a portion at least of said connecting means into communication with said transmission tube to establish a current of air through said tube for transmitting carriers, and means 100 for automatically throwing said blower into communication with the atmosphere after a predetermined interval.

5. In a pneumatic despatch tube apparatus, a tube for the transmission of carriers, a substantially constantly-operating blower or pump for compressed air, a conduit or connection between said blower or pump and said transmission tube provided with an outlet to the atmosphere, means 115 normally permitting the flow of air from said blower through said outlet, and compressed air actuated means, substantially independent of the flow of air through said conduit, for closing said outlet during a predetermined interval of time to establish a current of compressed air through said transmission tube for driving carriers therethrough. 120

6. In a pneumatic despatch tube apparatus, a tube for the transmission of carriers, said tube having a plurality of stations, a substantially constantly-operating blower or pump for compressed air, a conduit or connection between said blower or 130

5 pump and said transmission tube provided with a normally open outlet to the atmosphere through which air from said blower may flow, means for closing said outlet to establish a current of compressed air through said transmission tube for driving carriers therethrough, and means independent of said stations for automatically opening said air-outlet and short-circuiting the 10 current of air after a predetermined interval.

7. In a pneumatic despatch tube apparatus, a tube for the transmission of carriers, a substantially constantly-operating blower or pump for compressed air, a conduit or connection between said blower or pump and said transmission tube provided with an outlet to the atmosphere, means normally permitting the flow of air from said 15 blower through said outlet, means for closing said outlet to establish a current of compressed air through said transmission tube for driving carriers therethrough, and power actuated timed means for the opening 20 of said air outlet and the short-circuiting of said air current, said last mentioned means being substantially independent of the air flowing through said tube.

8. In a pneumatic despatch tube apparatus, a tube for the transmission of carriers, a constantly-operating blower or pump for compressed air, a conduit or connection between said blower or pump and said transmission tube provided with an outlet to the 35 atmosphere, means normally permitting the flow of air from said blower through said outlet, means for closing said outlet to establish a current of compressed air through said transmission tube for driving carriers therethrough, means for automatically 40 opening said air-outlet and short-circuiting the current of air after a predetermined interval, power actuated means for timing the flow of air through said tube, and means for 45 storing power to actuate said timing means.

9. In a pneumatic despatch tube apparatus, a conduit system comprising a transmission tube having a plurality of stations, continuously driven, means for creating a 50 flow of compressed air through said transmission tube for transmitting carriers therethrough, normally operative means for short circuiting said flow of air, and co-acting timing means for retarding actuation of said 55 short circuiting means, whereby to normally insure a carrier-transmitting flow of air through said transmission tube for a predetermined interval of time, connections for rendering said timing means operative by 60 compressed air and co-acting means for starting said timing means from any one of said plurality of stations.

10. In a pneumatic despatch tube apparatus, a conduit system comprising a transmission tube, means for creating a flow of

air through said transmission tube for transmitting carriers therethrough, normally operative means for short circuiting said flow of air, and co-acting timing means for retarding actuation of said short circuiting 70 means, said timing means adapted to be re-timed for each successive carrier transmitted without materially affecting the progress of a carrier already in course of transit through said tube. 75

11. In a pneumatic despatch tube apparatus, a conduit system comprising a transmission tube provided with a receiving part at which a carrier may be introduced, means for creating a flow of air through said transmission tube for transmitting carriers therethrough from said receiving part, means for normally short circuiting said flow of air when the transmission tube is idle, co-acting timing means, operated by compressed air, for maintaining said short circuiting means substantially inoperative for at least an interval of time sufficient for the normal transmission of a carrier a determined distance through said tube, a reservoir for the 80 compressed air for operating said timing means, and means, a portion of which is disposed adjacent said receiving part, for re-timing said timing means. 85

12. In a pneumatic despatch tube apparatus, a conduit system comprising a transmission tube having a plurality of stations, means for creating a flow of compressed air through said transmission tube for transmitting carriers therethrough, normally operative means for short circuiting said flow of air, co-acting timing means for retarding actuation of said short circuiting means, said timing means adapted to be re-timed for each carrier transmitted, and means for re-timing said timing means from any one of 90 said plurality of stations. 95

13. In a pneumatic despatch tube apparatus, a conduit system comprising a transmission tube, means for creating a flow of compressed air through said transmission tube for transmitting carriers therethrough, normally operative means for short circuiting said flow of air, co-acting timing means, movable independently of said short circuiting means, for retarding actuation of the latter, said timing means adapted to be re-timed for each carrier transmitted, and means a portion of which is adapted to be actuated by a carrier upon the insertion of the latter into the transmission tube for re-timing said timing means. 100

14. In a pneumatic despatch tube apparatus, a conduit system comprising a transmission tube having a plurality of stations, means for creating a flow of compressed air through said tube for transmitting carriers therethrough, means for short circuiting said flow of air after the lapse of an interval of time sufficient for the normal trans- 110 115 120 125 130

mission of the last of a plurality of carriers a determined distance through said tube, said last mentioned means including a timing device movable independently of said 5 short circuiting means and adapted to be re-timed while in operation, and means, a portion of which is at each of said plurality of stations, for re-timing said timing means.

In testimony whereof, I have signed my name to this specification in the presence 10 of two subscribing witnesses, this 29th day of November A. D. 1911.

MERTON L. EMERSON.
